Primary Examiner — Jack Reickel*Assistant Examiner* — Rene H. Kadoo(74) *Attorney, Agent, or Firm* — Rankin, Hill & Clark LLP(57) **CLAIM**

The ornamental design for a jar opener, as shown and described.

DESCRIPTION

FIG. 1 is a top, left side perspective view of a jar opener showing our new design;

FIG. 2 is a front elevation view FIG. 1;

FIG. 3 is a rear elevation view FIG. 1;

FIG. 4 is a right side elevation view FIG. 1;

FIG. 5 is a left side elevation view FIG. 1;

FIG. 6 is a top plan view FIG. 1;

FIG. 7 is a bottom plan view FIG. 1;

FIG. 8 is a bottom, left side perspective view of FIG. 1; and,

FIG. 9 is a bottom, left side perspective view of FIG. 1.

The broken lines in the drawings depict portions of the jar opener that form no part of the claimed design.
